UNITED STATES PATENT OFFICE

LILLYMAY LOWERY, OF LOS ANGELES, CALIFORNIA

DESIGN FOR AN AUTOMOBILE RADIATOR ORNAMENT OR SIMILAR ARTICLE

Application filed October 26, 1931. Serial No. 41,520. Term of patent 3½ years.

To all whom it may concern:

Be it known that I, LILLYMAY LOWERY, a citizen of the United States, residing at 1221 N. Vermont Ave., Los Angeles, in the county of Los Angeles and State of California, have invented a new, original, and ornamental Design for Automobile Radiator Ornament or Similar Article, of which the following is a specification, reference being had to the accompanying drawing, forming part thereof.

I claim:

The ornamental design for an automobile radiator ornament or similar article as shown.

LILLYMAY LOWERY.
